UNITED STATES PATENT OFFICE.

JAMES J. REED, OF NEW PHILADELPHIA, OHIO.

VENDING APPARATUS.

SPECIFICATION forming part of Letters Patent No. 728,412, dated May 19, 1903.

Application filed March 14, 1902. Serial No. 98,233. (No model.)

To all whom it may concern:

Be it known that I, JAMES J. REED, a citizen of the United States, residing at New Philadelphia, in the county of Tuscarawas and State of Ohio, have invented certain new and useful Improvements in Vending Apparatus; and I do hereby declare the following to be a full, clear, and exact description of the invention, such as will enable others skilled in the art to which it appertains to make and use the same.

This invention relates to improvements in vending-machines of that type in which the movement of mechanism to feed the article on sale to an accessible point or réceptacle is permitted upon the insertion of a coin in a slot or guideway provided to receive it.

The invention has for its object the production of a machine of this character which while especially designed for vending cigars may be employed for vending other goods or commodities in package form or otherwise and which embodies simple and efficient feeding devices operative upon the deposit of a coin to enable the deposit or to operate the machine to cause the delivery of the goods.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a vending apparatus embodying my invention. Fig. 2 is a vertical longitudinal section of the same on the central line of one of the sets of coin-controlled feeding devices. Fig. 3 is a vertical cross-section of the same on line 3-3 of Fig. 2. Fig. 4 is a horizontal section, on an enlarged scale, looking down upon one of the reciprocating feed-plates. Fig. 5 is a vertical longitudinal section, on an enlarged scale, showing in full lines the normal position of the feed devices and in broken lines the manner in which the feed-plate is actuated by the slide upon the deposit of a coin. Fig. 6 is a top plan view of two of the feed-plates and the parts coöperating therewith.

Like reference characters indicate corresponding parts in the following description and drawings hereto attached.

The casing 1 of the apparatus is of suitable form and size to inclose the operative parts and goods to be vended and comprises a base 2, a hinged top or section 3, provided at its rear with a chamber or compartment 4 to contain the goods to be vended, and a door 5, giving access to said chamber to enable the goods to be placed therein and the empty boxes when the apparatus is used for the vending of cigars or other boxed goods to be conveniently removed. As shown in the present instance, the top section is hinged at one side, so that it may be turned up and swung laterally to expose the interior of the base 2, while the door 5 is hinged at its lower edge to turn down. Suitable locks or fastenings are to be employed in practice to hold these parts closed to prevent unauthorized persons from gaining access to the interior of the machine.

In order to make clear the operation of the invention, I have shown the same as used for the vending of cigars, without, however, intending to limit the invention to the vending of goods of this character. When so used, the box or boxes 6, containing the cigars, are placed in the chamber 4, and each box is formed in its bottom with a discharge-aperture 6' to allow the cigars to feed out, and the said chamber 4 is provided at top with a transparent panel 7 to enable the boxes, with their contents, to be viewed. The case 1 is constructed to provide at the front a receptacle 8, in which the cigars are delivered, and the bottom of this receptacle is extended back

on an upward incline to form a chute 9, down which the cigars when deposited thereon travel by gravity to said receptacle. Above the receptacle 8 a till or shallow tray 10 is provided to receive the deposited coin, which may be removed upon lifting the section 3. The rear portion of the section is closed at bottom by a wall 11, above the rear portion of which is arranged a transverse shelf 12, while the front portion of said section is open at bottom for the feed of the cigars to the chute 9 and coin to the tray 10. The boxes 6 rest upon the shelf 12 and ledges 13, arranged between said shelf and front wall of the compartment 4, with their discharge-apertures 6' located above the space between the ledges.

Any desired number of boxes containing different brands or grades of cigars may be placed in the compartment 4, and the sets of vending devices will correspond in number 5 therewith and will be constructed to operate when required upon the deposit of coins of different denominations. In the present instance I have shown the apparatus provided with three sets of vending devices; but as 10 the construction is the same in each case a description of one will suffice for all.

The opening 6' in the bottom of each box 6 is normally closed by a feed plate or board 14, which slides between suitable side guides 15 and between the wall 11 and shelf 12. The rear portion of this plate closes the opening 6', and at or about its center said plate has a transverse slot or feed-passage 16, which when the plate is moved rearwardly to its fullest 20 extent registers with said aperture 6', allowing one or more cigars to drop down onto the chute 9. It will of course be understood that the size of this slot 16 will determine the number of cigars which are to be delivered in exchange for a coin of a certain denomination. 25 The front portion of the plate is formed with a longitudinal slot or guideway 17, which communicates a short distance in rear of its forward end with a transverse slot 18. A pin 19 projects downward into the guideway 17 and is carried by a superposed slide 20. This slide 20 moves between suitable guides 21 and is attached to a knob or handpiece 22 by a stem or shank 23, fitted to slide in a slot 24, 30 formed in the top wall of the front portion of the section 3. The knob or handpiece is thus located on the exterior and constitutes a means whereby the slide and feed-plate may be operated upon the deposit of a coin. The 35 coin is deposited in a slot 25, located adjacent to the lower end of the slot 24 and immediately above the cross-slot 18 in the feed-plate 14 when said plate is in its normal position.

The operation is as follows: The pin 19 40 normally slides freely in the slot 17, so that the feed-plate will not be affected by the movement of the slide 20 until a coin is deposited in the slot 25. The coin inserted through the slot 25 drops by gravity into the 45 cross-slot 18 of the feed-plate and is held in place by the bottom wall 26, which forms a support therefor. As the slot 18 is of a length approximating the diameter of the coin, the latter will lie in front of the pin 19 and bridge 50 the slot 17, so that when the slide 20 is moved rearwardly through the medium of the knob 22 the pin will contact with the coin, which will form a connection to cause the feed-plate to move with the knob. The rearward movement 55 of the slide thus brings the feed-opening 16 below the feed-aperture 6' in the box 6, allowing one or more cigars to drop into said feed-opening 16 and rest on the wall 11, and at this time the shank 23 will contact 60 with the upper wall of the slot 24, thereby removing the pressure of the pin 19 from the 65

coin, allowing the latter to drop down into the tray 10. There being now no connection between the slide and feed-plate, the latter, which slides, as shown, in an inclined path, 70 returns to its normal position by gravity, and when the feed-opening 16 clears the forward edge of the wall 11 the cigar drops through and down onto the chute 9, whence it rolls by gravity to the delivery-receptacle 8. The 75 lower edge of the coin when held by the pin 19 during the movement of the feed-plate travels in a groove 27 in the bottom wall or support 26, and the bottom wall of this groove is formed with ratchet-teeth 28, inclining inwardly and upwardly, so as to prevent the feed-plate from returning to its normal position before the coin has been released. The wall 26 has a slot 29 below the slots 18 and 25 to allow slugs, tokens, and coins of a smaller 85 diameter than those said slots are formed to receive to pass out of the machine and drop into the receptacle 8, so as to defeat any attempt which may be made to operate the machine and obtain goods by the use of any but 90 the proper coin.

From the foregoing description, taken in connection with the accompanying drawings, the construction, mode of operation, and advantages of the invention will be readily understood, and it will be seen that an exceedingly efficient construction of vending-machine is provided. 95

Changes in the form, proportion, and minor details of construction may be resorted to 100 within the scope of the invention without departing from the spirit thereof.

Having thus described the invention, what is claimed as new is—

A vending-machine comprising a goods-compartment, a forwardly and downwardly inclined support arranged beneath the goods-compartment and extended in front thereof and having a delivery-opening for the goods and coin and having a series of notches for 105 coöperation with the coin to prevent backward movement of the slide, a feed-plate slidably mounted upon the support and movable beneath the goods-compartment and having a delivery-opening, a coin-slot and a 110 longitudinal slot, an operating-slide movable over the feed-plate and having a coin-opening 115 to register with the coin-slot of the feed-plate, the slide and feed-plate being returnable to a normal position by means of gravity, a pin pendent from the slide and extended into the longitudinal slot of the feed-plate, a coin-tray arranged beneath the front portion of the support, and a chute arranged beneath the coin-tray and extended in the front and in 120 the rear thereof, substantially as shown. 125

In testimony whereof I affix my signature in presence of two witnesses.

JAMES J. REED. [L. S.]
